UNITED STATES PATENT OFFICE.

LEVI D. MECKLEY, OF WINDGAP, PENNSYLVANIA.

RAILROAD-RAIL.

No. 861,041.

Specification of Letters Patent.

Patented July 23, 1907.

Application filed March 5, 1907. Serial No. 360,695.

To all whom it may concern:

Be it known that I, LEVI D. MECKLEY, a citizen of the United States, residing at Windgap, in the county of Northampton and State of Pennsylvania, have invented new and useful Improvements in Railroad-Rails, of which the following is a specification.

This invention relates to railroad track construction and relates more particularly to a composite rail composed of separate tread and base sections that are bolted or otherwise suitably secured together.

The invention has for one of its objects to improve and simplify the construction of rails of this character so as to be comparatively simple and inexpensive to manufacture, easy to put together, and constitute a strong and durable rail.

A further object of the invention is to provide a rail having reversible and renewable tread sections that are bolted to the base section, the arrangement being such that the tread sections can be readily taken out and reversed when worn on one side or replaced by new ones when worn on both sides, without requiring the base sections to be removed from the cross-ties.

A still further object of the invention is the provision of a railroad rail so constructed that a track can be maintained in proper repair at a minimum of expense and labor and that smooth running of the trains thereover without noise and shock is possible.

With these objects in view and others, as will appear as the description proceeds, the invention comprises the various novel features of construction and arrangement of parts which will be more fully described hereinafter and set forth with particularity in the claims appended hereto.

In the accompanying drawing which illustrates one of the embodiments of the invention, Figure 1 is a side elevation of a portion of the composite rail. Fig. 2 is a similar view of the opposite side. Fig. 3 is a transverse section on line 3--3, Fig. 1. Fig. 4 is a transverse section on line 4--4, Fig. 1. Fig. 5 is a horizontal section on line 5--5, Fig. 1.

Similar reference characters are employed to designate similar parts throughout the figures.

Referring to the drawing, A designates the base sections, and B, the tread sections of the rail. These sections may be of any desired length and they may be assembled with the meeting edges of the base sections in any desired relation with the meeting edges of the tread sections. The base sections A each comprise a base 1 and a central upwardly and longitudinally extending web 2 that is grooved longitudinally to form a pocket 3 that tapers or contracts downwardly as shown clearly in Figs. 3 and 4. In other words, the web 2 of each base section is composed of two spring plates which are adapted to be clamped on the tread section or sections. Each tread section B comprises a head 4 of usual form and a central longitudinal tongue 5 depending from the

head and adapted to enter the pockets 3 of the base sections. At the root of the tongue 5 are grooves 6 of any suitable shape into which the upper edges of the plates of the web 2 engage.

The tongues 5 of the tread sections are tapered vertically so as to snugly fit in the pockets of the base sections and the webs 2 and tongues 5 are provided with bolt openings 7 that are elongated in the direction of the length of the rail and the bolts that pass through these openings for securing the sections together are of less size than the openings so as to permit the parts of the rails to expand or contract under temperature changes.

The bolts 8 for securing the sections of the rails together have elongated heads 9 and shanks 10, the shank being of sufficient length to extend entirely through the openings of the plates of the webs and projecting from the shanks 10 are threaded stud portions 11 for receiving the tightening and jam nuts 12 and 13. Interposed on the stud portion 11 between the tightening nut 12 and the adjacent side of the web 2 is a washer 14 that is elongated horizontally and provided with a recess 15 for receiving the outer end of the shank 10, whereby the said shank holds the washer in fixed position and prevents relative turning. The stud portion 11 has a transverse opening 16 for receiving a key 17 that engages in a diametrical slot 18 in the outer surface of the jam nut as shown clearly in Fig. 3, and the smaller end of the wedge shaped key is bent back against the jam nut, as indicated at 19.

In the operation of laying the track, the base sections A are placed on the cross ties and spiked thereto in the usual manner in the case wooden ties are employed or bolted or otherwise suitably secured when metal or concrete ties are employed. These base sections are laid with great precision for the reason that they are intended to be permanently secured in place, since their removal is rendered unnecessary in the repair of the road. The tread sections B are then assembled by inserting the tongues 5 into the pockets 3 of the base sections and forcing the tongues home, whereupon the upper edges of the spring plates of the webs 2 enter the recesses or longitudinal grooves 6 in the head portions 4. The bolts 8 are then inserted into the openings of the rail sections and the washers and nuts applied and securely locked in position. In drawing up on the nuts 12, the spring plates of the webs 2 are firmly clamped to the tongues 5, whereby the tread sections are held in perfect alignment and a smooth and continuous bearing surface formed for the car wheels to pass over. When the rails become worn to such an extent that repair is necessary, the bolts are taken out and the tread sections removed by prying upwardly thereon with a suitable instrument and the tread sections are reversed so as to bring the unworn sides of the head portions of the tread sections on the

inside of the rails, after which the said sections are replaced and bolted in position. Thus, it will be seen that the base sections do not have to be removed from the ties, that the tread sections can be used twice as long as usual before replacing is necessary, and that since the rail sections are comparatively light and short, a less number of hands are required to take out the tread sections for reversal or renewal. Another important advantage is that the rails do not have to be removed from the ties after once being laid, thus obviating re-spiking and the leaving of spike holes in the ties into which rain enters and rots the latter.

I have described the principle of operation of the invention, together with the device which I now consider to be the best embodiment thereof, but I desire to have it understood that the device shown is merely illustrative and that such changes may be made as desired as are within the scope of the claims.

Having thus described the invention, what I claim is:

1. A rail comprising separate sections, a pocket on one

section, a tongue on the other section extending into the pocket, said tongue and walls of the pocket being provided with elongated openings, a bolt having an elongated shank extending through the openings and provided with a threaded stud portion, a recessed washer on the stud portion fitting the shank to prevent relative turning, and tightening and jam nuts on the stud portion for securing the parts together.

2. A rail comprising separate sections, a web on one of the sections composed of parallel spring plates having elongated openings, a tongue on the other section engaging between the plates and provided with an elongated opening, a bolt having a flattened shank engaging in the openings of the tongue and plates and provided with a stud portion having an aperture, a recessed washer on the stud fitted to the shank to prevent turning, tightening and jam nuts on the stud portion, the jam nut having a diametrical recess, and a key extending through the aperture of the stud portion and engaging in the recess of the jam nut.

In testimony whereof, I affix my signature in presence of two witnesses.

LEVI D. MECKLEY.
